LOCKING PEN AND PENCIL COMPASS AND
DIVIDER

Eulalio M. Varona, Oscar B. Varona, and Olivio B. Varona, Manila, Republic of Philippines, assignors of one-half to Manuel Salientes, Jose B. Ramos, and Ciriac Montano, all of Washington, D. C., jointly

Application October 18, 1950, Serial No. 190,756

7 Claims. (Cl. 33—27)

1

This invention relates to drawing instruments particularly of the type used by Engineering Draftsmen, and in particular a combination instrument having three legs with a pair of points in two of the legs forming a divider and with a reversible bar having a pen on one end and a pencil point in the other removably mounted on the third leg.

The purpose of this invention is to provide a universal drawing instrument that may be used as a divider and that may also be used for describing circles or arcs in both pencil and ink lines.

The invention also includes a drawing instrument having cam locking means included therein wherein points may be set to dimensions and readily locked in the positions to which they have been set.

In the conventional type of compass and divider points or a point and a pencil or pen are accurately adjusted to a dimension and it is difficult to lock the points or the point with the pencil or pen in the adjusted position. With this thought in mind this invention contemplates a combination drawing instrument having three members pivotally mounted on a common pin with points adjustably mounted in two of the members and with a bar having a drawing pen on one end and a pencil point on the other removably mounted on the third member, and with the members provided with hubs having cam surfaces positioned to lock two of the members as a third member is moved upwardly.

The object of this invention is, therefore, to provide, in a combination drawing instrument having three legs, means for locking two of the legs by a third leg.

Another object of the invention is to provide a combination drawing instrument that may readily be converted from a pencil compass to a compass having a pen therein whereby lines described by the pencil may be inked with the same instrument.

A further object of the invention is to provide a combination drawing instrument having divider and pen and pencil compass elements with locking means incorporated in the elements, which is of a simple and economical construction.

With these and other objects and advantages in view the invention embodies a center leg having a point adjustably mounted in one end with a hub having cam surfaces on the ends thereof positioned on the opposite end, a coacting leg also having a point adjustably mounted in one end and having a hub with a cam shaped inner sur-

2

face on the other positioned to coact with the cam surface on one side of the hub of the center leg, and a compass leg having pen and pencil points on opposite ends of a bar carried thereby also having a cam surface on a hub at the upper end positioned to coact with the cam surface of the hub of the center leg, and a pin pivotally retaining the legs in assembled relation.

Other features and advantages of the invention will appear from the following description taken in connection with the drawings wherein:

Figure 1 is a front elevational view of the combination instrument with part of one of the legs thereof broken away showing the adjustable mounting of a point in the end thereof.

Figure 2 is a similar elevational view showing the divider points extended for use with the pen and pencil mounting bar removed.

Figure 3 is a detail illustrating an elevational view of the pen and pencil point mounting bar.

Figure 4 is a detail on an enlarged scale showing the mounting of the pen nibs in the end of the bar.

Figure 5 is a cross section taken on line 5—5 of Figure 1 showing the mounting of the pen and pencil mounting bar between ears of the compass leg of the instrument.

Figure 6 is a cross section taken on line 6—6 of Figure 1 showing the sliding collar for securing the pen and pencil mounting bar to the leg of the instrument.

Figure 7 is a cross section taken on line 7—7 of Figure 3 showing the collar for securing the pencil point in the end of the pen and pencil mounting bar.

Figure 8 is a detail showing an exploded view illustrating the hub at the upper end of the leg and showing the hub separated.

Figure 9 is a detail illustrating a section through the hub of the legs showing the pin extended through the hub and showing the parts in the free position.

Figure 10 is a similar view showing the side leg moved upwardly to the locking position.

Referring now to the drawings wherein like reference characters denote corresponding parts the combination drawing instrument of this invention includes a center leg 10, a coacting divider leg 11, a compass leg 12, a pin 13 for pivotally connecting the legs and a mounting bar 14 having a pen 15 on one end and a pencil point 16 clamped in the opposite end.

The center or first leg 10 is formed as illustrated in Figures 1 and 8 with a point 17 adjustably secured in a socket 18 by a set screw 19.

and with a hub 20 on the upper end, the ends of which are provided with cam surfaces 21 and 22. The hub 20 may also be provided with a knob 23 by which the instrument may be held in use, and the intermediate part thereof is provided with an opening 24 through which the pin 13 extends, as shown in Figure 9.

The divider leg 11 is provided with a similar socket 25 in the outer end in which a point 26 is adjustably held by a set screw 27, and the opposite end is provided with a hub 28 having a cam surface 29 thereon and having an opening 30 extended therethrough for receiving the pin 13.

The compass leg 12 is also provided with a hub, as indicated by the numeral 31 and the inner surface of this hub is provided with a cam surface 32 and an opening 33 extends through the hub for receiving the pin 13. The outer surface of the hub 31 may be countersunk as indicated at the point 34 to receive the head of the pin 13.

The lower part of the compass leg 12 is provided with projections or ears 35 and 36 between which the bar 14 is frictionally held and with the bar positioned between the ears of the leg 12 a collar 37, slidably mounted on the bar 14, is moved upwardly over the lower end 38 of the leg 12 to rigidly clamp the pen and pencil point mounting bar 14 between the ears 35 and 36 and against the outer surface of the leg 12. The upper part of the leg 12 may be provided with a boss 39 against which the bar 14 may be positioned, as shown in Figure 1.

As illustrated in Figure 4 the nibs 40 and 41 of the pin are secured in a socket 42 at one end of the bar 14 and the nibs are provided with a cam 43 whereby the positions of the nibs are adjustable to form a thin or a thick line as may be desired.

The nibs are also provided with shoulders 52 and 53 that are positioned to engage flanges 54 and 55 of the cam 43 to limit outward movement of the cam.

The opposite end of the bar 14 is provided with a pair of clamping jaws 44 and 45 which are formed with sloping outer surfaces and a collar 46 slidably mounted on the said sloping outer surfaces provides means for clamping a pencil point 16 between the jaws. A slot 47 may be provided through the upper end of the bar to provide resiliency in the supporting elements of the jaws.

The pin 13 is provided with a countersunk head 50 and a flat head 51 is provided on the opposite end as shown in Figures 9 and 10.

With the parts arranged in this manner the instrument may be used as a pair of dividers, as illustrated in Figure 2 and with the points set to a dimension a third or compass leg 13 is moved upwardly to lock the legs carrying the points in position.

The cam surfaces are sloped at an angle of less than 90 degrees to the axes of the hubs of the parts whereby upward movement of either of the legs 11 and 12 spreads the hub longitudinally of the pin and causes a clamping action which locks the legs in the position to which they have been set.

When it is desired to use the device as a pencil compass the position of the bar 14 is reversed whereby the pencil point 16 extends downwardly, opposite to the position illustrated in Figure 1 and when it is desired to use the device as a pen compass the bar 14 is positioned between

the ears 35 and 36 and the collar 37 moved upwardly over the point 38 thereby locking the mounting bar 14 in position upon the compass leg 12.

5 The leg 12 is also provided with ears 56 and 57, similar to the ears 35 and 36, which frictionally hold the leg 10 against the adjacent surface of the leg 12 when the device is used as a pair of dividers.

10 It will also be understood that the bar 14 may be removed from the instrument so that the pen or pencil may be used independently.

15 It will also be understood that other modifications within the scope of the appended claims may be made in the design and arrangement of the parts without departing from the spirit of the invention.

What is claimed is:

20 1. A drawing instrument comprising a pair of divider legs and a compass leg, each of said legs having hubs on one of the ends thereof and said hubs having cam surfaces on abutting faces thereof, a pin extended through the hubs providing a pivotal mounting for the legs, and points carried by the ends of the legs opposite to the ends on which the hubs are positioned.

25 2. A drawing instrument comprising a pair of divider legs and a compass leg, each of said legs having hubs on one of the ends thereof and said hubs having cam surfaces on abutting faces thereof, a pin extended through the hubs providing a pivotal mounting for the legs, points carried by the ends of the legs opposite to the ends on which the hubs are positioned, and means adjustably mounting the points in the legs.

30 3. A drawing instrument comprising a pair of divider legs and a compass leg, each of said legs having hubs on one of the ends thereof and said hubs having cam surfaces on abutting faces thereof, a pin extended through the hubs providing a pivotal mounting for the legs, points carried by the ends of the legs opposite to the ends on which the hubs are positioned, means adjustably mounting the points in the legs, and means for reversing the position of one of the points.

35 4. In a drawing instrument, the combination which comprises a pair of legs each having a hub on one end thereof with coacting cam faces on the inner surfaces of the hubs and having point receiving sockets in the other ends of said legs, set screws positioned in said legs to extend into said sockets, points adjustably held by the set screws in the said sockets, a pin extended through the hubs of the legs providing pivotal mounting means therefor, and a third leg also having a hub with a cam surface thereon mounted on said pin and positioned to cooperate with the cam faces of the former legs whereby with the legs in which the points are positioned set to a dimension actuation of the third leg clamps the legs carrying the points.

40 5. In a drawing instrument, the combination which comprises a pair of legs each having a hub on one end thereof with coacting cam faces on the inner surfaces of said hubs and having points on the opposite ends, a pin extended through the hubs of the legs providing pivotal mounting means therefor, a third leg also having a hub with a cam surface thereon mounted on said pin and positioned to cooperate with the cam faces of the former legs whereby with the legs in which the points are positioned set to a dimension actuation of the third leg clamps the

legs carrying the points, and means reversibly mounting pen and pencil points on the said third leg.

6. In a drawing instrument, the combination which comprises a pair of legs each having a hub on one end thereof with coacting cam faces on the inner surfaces of said hubs and having points on the opposite ends, a pin extended through the hubs of the legs providing pivotal mounting means therefor, a third leg also having a hub with a cam surface thereon mounted on said pin and positioned to cooperate with the cam faces of the former legs whereby with the legs in which the points are positioned set to a dimension actuation of the third leg clamps the legs carrying the points, said third leg having spaced parallel ears extended from the sides thereof adapted to hold a bar having a pencil point at one end and a pen in the other with the bar frictionally held between the ears of the said third leg and a collar slidably mounted on the bar and positioned to extend over the end of the said third leg for clamping the bar in operative position upon the third leg.

7. In a compass, the combination which comprises a center leg having a hub with an opening extended longitudinally therethrough positioned on one end and having a point on the opposite end, said hub having cam surfaces on the ends, a compass leg having a hub also with an opening extended longitudinally therethrough on one end and having a cam surface on one end of the hub, a divider leg also having a hub with an opening extended longitudinally therethrough

on one end and said hub having a cam surface on one end thereof, a pin extended through the openings of the hubs of the legs pivotally connecting the legs, said cam surfaces positioned whereby upward movement of one of the legs with the other legs extended downwardly clamps the legs preventing movement thereof, a bar removably clamped to said compass leg, and means for mounting a pencil point on one end of the bar and a pen on the opposite end of the bar.
